UNITED STATES PATENT OFFICE.

ADOLPHE WM. SCHMIDT, OF LEWISTON, IDAHO.

ROLLER-MILL SCRAPER.

1,272,863.

Specification of Letters Patent. Patented July 16, 1918.

Application filed June 21, 1917. Serial No. 176,241.

To all whom it may concern:

Be it known that I, ADOLPHE W. SCHMIDT, a citizen of the United States, residing at Lewiston, in the county of Nez Perce and State of Idaho, have invented certain new and useful Improvements in Roller-Mill Scrapers; and I do declare the following to be a full, clear, and exact description of the invention, such as will enable others skilled 10 in the art to which it appertains to make and use the same.

My invention relates to that class of devices intended to prevent the accumulation of crushed material on the rollers of the so-called roller mills. I am aware that numerous devices have heretofore been devised for this purpose, but all of these devices, in so far as I am advised, have been mounted beneath the rollers and cause considerable 20 trouble whenever it is necessary to gain access thereto for cleaning or other purposes.

It is the principal object of my invention to provide simply constructed and inexpensive scrapers which may be located either 25 on the upper side of the rollers or at any other suitable location other than at the bottom thereof, thus making the devices easily accessible whenever necessary.

With the foregoing general object in view, 30 the invention resides in the novel features of construction and unique combination of parts to be hereinafter fully described and claimed, the descriptive matter being supplemented by the accompanying drawings 35 which form a part of this specification and in which:

Figure 1 is a vertical transverse section of a roller mill showing the application of the invention thereto;

40 Fig. 2 is a horizontal section on the plane of the line 2—2 of Fig. 1;

Fig. 3 is a perspective view of the invention detached from the mill; and

45 Fig. 4 is a similar view showing more particularly the adjustable connection between the attaching feet and the scraper bars.

In the drawings above briefly described, the numeral 1 designates a pair of rollers of 50 a common type of roller mill, said rollers being positioned beneath the hopper 2 into which the material to be crushed or rolled is fed. It is the intention of the present device to provide novel means for scraping the 55 material from the rollers 1 so that it will not accumulate thereon, and to this end I

employ the features of construction now to be described.

A pair of horizontally elongated supports 3, preferably cast from iron or the like, are 60 secured in any preferred manner to the ends of the rolling chamber 4, on the interior of the latter, the centers of said supports preferably having longitudinal slots 5 through which bolts or the like 6 are passed. The 65 ends of the supports 3 are provided with pairs of ears 7 extending longitudinally thereof and receiving therebetween additional ears 8 on the upper ends of arms 9, the lower ends of said arms preferably having 70 integral weighted feet 10 which extend laterally therefrom as shown. A pair of scraper bars 11 extend longitudinally on the rollers 1 and are provided at their ends with slots 12 through which fastening screws or 75 other devices 13 pass, said screws or the like being employed for securing the bars 11 adjustably to the feet 10. By connecting the bars 11, by means of the slots 12 and 13 with the feet 10, the device is adjustable for use 80 in connection with rolling mills having rollers of different lengths.

When installing the invention, the supports 3 are secured by the bolts 6 or other suitable fastening means, to the ends of the 85 rolling chamber 4, on the interior of the latter, the arms 9 then depending from the ends of said supports as will be clear from Figs. 1 and 2. When in this position, the arms 9 support the scraper bars 11 either on opposite sides of a pair of co-acting rollers as shown in Fig. 1 or on the opposed sides of a single roller. If the last named arrangement is employed, two sets of scraper bars 90 will be employed for every coacting pair of rollers. It will be observed that the bars 11 contact with the rollers 1 at such points as to permit them to be readily accessible in case the cleaning thereof should be necessary, or if repairs need be made. For these 95 reasons, the improved construction is much more advantageous than any previously employed.

From the foregoing, taken in connection with the accompanying drawings, it will be 105 obvious that although the invention is of comparatively simple and inexpensive nature, it will be highly efficient and durable. Since probably the best results are obtained from the specific construction shown and described, such construction constitutes the 110 preferred form of the improved scraper. I

wish it understood, however, that within the scope of the invention as claimed, numerous minor changes may be made without sacrificing the principal advantages.

5 I claim:

1. A roller mill scraper comprising a pair of arched end members having vertically movable ends, means for securing the central portions of said members to the ends of the crushing chamber of the roller mill, and roller scraping bars secured at their ends to said vertically movable ends of said end members.

10 2. A roller mill scraper comprising a pair of arched end members each formed of a central and two end sections, said central sections having openings to receive bolts for securing them to the ends of the crushing chamber of a roller mill, each end of said

central sections being increased in width 20 and formed with a pair of horizontally spaced ears, the upper ends of said outer sections having ears received between said pair of ears and pivoted thereto, laterally extending flat shoes on the lower ends of said outer sections, the shoes of each end member extending toward those of the other, roller scraping bars whose ends contact with the lower faces of said shoes, and fasteners 25 securing said bars and said shoes together. 30

In testimony, whereof I have hereunto set my hand in the presence of two subscribing witnesses.

ADOLPHE WM. SCHMIDT.

Witnesses:

AUGUST VAN DYK,
NEAL N. NELSON.
